UNITED STATES PATENT OFFICE.

JOHN B. DAVIDS, OF DARTMOUTH, MASSACHUSETTS, ASSIGNOR TO E. M. CHISHOLM DAVIDS, OF SAME PLACE.

GAME-BOARD.

SPECIFICATION forming part of Letters Patent No. 519,324, dated May 8, 1894.

Application filed July 7, 1892. Serial No. 439,267. (No model.)

To all whom it may concern:

Be it known that I, JOHN B. DAVIDS, a citizen of the United States, residing at North Dartmouth, in the county of Bristol and State of Massachusetts, have invented certain new and useful Improvements in Game-Boards, of which the following is a specification, reference being had to the drawings hereto annexed, in which—

10 Figure 1. is a view in perspective of my improved game board. Fig. 2. is a view in vertical section of the device for casting the quoits; and Figs. 3. and 4. are views of some of the details.

15 Similar letters refer to similar parts in the several views.

20 *a*, represents my improved game board consisting of a shallow tray, having on its inside surface, the raised edge *b*, surrounding the pins or stakes *c*. The corners of the board are provided with the spring casting devices *e*, consisting of the pivoted lever *f*, adapted to be operated by a spring impelled plunger. At the foot of the lever, is secured to the board, 25 the block, *g*. (Fig. 4.) having the curved notch *h*, adapted to fit the curve of the rings *d*.

The game is played by laying a ring *d*, against the foot of the lever *f*, with its edge

resting in the curved notch *h*, and casting it, by means of the spring plunger, or by the 30 sudden stroke of the finger, on the top of the lever *f*; the object being, to give the ring such a cast, as to land it within the inclosure of the edge *b*, and cause it to encircle, one of the stakes *c*. When it is desired to give the 35 cast, by means of the finger on the lever *f*, instead of by the plunger, the block *l*, (Fig. 3.) is placed under the shoulder *k*, of the plunger, which block, holds it, in a retracted position. 40

I claim—

A game apparatus consisting of the shallow quadrangular tray *a*, having its upper surface divided into two fields, by a raised edge *b*, and having its inner field provided with the 45 pins or stakes *c*; and having the corners of said tray provided with pivoted levers *f*, adapted to be actuated by a spring impelled plunger, or the finger; and metallic rings, adapted to be cast by the levers *f*, within the 50 central field and encircle the pins *c*, all as shown and described.

JOHN B. DAVIDS.
